UNITED STATES PATENT OFFICE.

AUGUSTUS F. KLASING, OF CHICAGO, ILLINOIS, ASSIGNOR TO THE KLASING CAR BRAKE COMPANY, A CORPORATION OF COLORADO.

APPARATUS FOR MANIPULATING RAILWAY-CAR BRAKES.

Application filed October 8, 1920. Serial No. 415,572.

To all whom it may concern:

Be it known that I, AUGUSTUS F. KLASING, a citizen of the United States, residing at Chicago, in the county of Cook and State 5 of Illinois, have invented certain new and useful Improvements in Apparatus for Manipulating Railway-Car Brakes, of which the following is a specification.

My invention relates to railway car brake mechanisms and particularly to manually operated apparatus for applying and releasing the brakes of a railway car, for example, a freight car, in switching or on other occasions when the brakes are applied and released manually. All railway cars are supplied with manually operated brake mechanism in addition to the air brake mechanism. The manually operated apparatus is of special importance in connection with freight 20 cars on which the air brake mechanism is not employed when the cars are being switched. The hand braking mechanism, consisting of a brake staff around which the brake chain is wound and operated by a hand wheel, with which freight cars are usually provided, is not sufficiently powerful, is slow of operation, uncertain in its functioning, and requires the use of both hands of the brakeman in operating the same, 25 thereby causing accidents because of the insecure hold which he has on the car, besides resulting in damage to cars and cargoes through collision. This mechanism, which is inherently objectionable for the foregoing 30 reasons, is rendered entirely inadequate at the present time, because of the increasing weight of the modern freight cars and the speed they attain in switching, especially in a hump yard.

One of the objects of my invention is to provide novel and improved apparatus for quickly removing slack from and applying great power to the brakes, as they are being set and which will be simple, strong and compact, and will not be rendered inoperative because of ice, snow, cinders, and the like.

A further object is to provide in apparatus of this character, means for maintaining 45 the brakes in set position, which means may

itself be set to release the brakes and which will be automatically reset to operative position after the brakes have been released.

The invention consists in the novel constructions, combinations and devices to be 55 hereinafter described and claimed, for carrying out the above stated objects and such other objects as will appear from the following description.

The invention is illustrated in a preferred 60 embodiment in the accompanying drawings, in which:

Fig. 1 is an elevation of the end portion of a box car, to which the manually operated apparatus has been applied. 65

Fig. 2 is a vertical section taken along the line 2—2 of Fig. 1.

Fig. 3 is a fragmentary vertical section taken along the line 3—3 of Fig. 4.

Fig. 4 is a transverse vertical section taken 70 along the line 4—4 of Fig. 3 and illustrating the interior of the housing of the apparatus.

Fig. 5 is a plan section taken along the line 5—5 of Fig. 4. 75

Like characters of reference designate like parts in the several figures of the drawings.

The brake apparatus of my invention may be applied to various types of railway cars. 80 The preferred form of the invention herein disclosed is illustrated as installed upon a box car. In Fig. 1, 10 designates the body of the car, to the end wall 11 of which the brake apparatus is attached. The brake apparatus consists of a mechanism generally designated as 12 for manually applying power, a tension rod 13, a transmission device 14 for transmitting the power to the brakes through the chain 15 and also in the 85 embodiment shown, acting to quickly remove the slack from the apparatus prior to the contact of the brake shoes with the wheels. It is obvious that any other suitable form of transmission device may be employed in 90 place of the transmission device 14, herein illustrated, the results accomplished depending upon the particular type of transmission device employed. For instance, a simple bell crank would properly transmit the ten- 95

sion from the tension rod to the chain 15, though without accomplishing the additional quick take-up of which the transmission device 14 herein illustrated is capable.

5 This device consists of a rolling lever bell crank 16, to one end 17 of which the tension rod 13 is connected. The opposite member of the bell crank is constructed in the form of a winding surface 18 upon 10 which the chain 15 is adapted to wind during the oscillation of the bell crank. The bell crank is preferably provided with a moving fulcrum consisting of a fixed, inclined rack 19 provided on a bracket 20 secured to the lower corner of the car, and a 15 rolling fulcrum 21 consisting of a sector of a gear adapted to mesh with the rack 19. The bell crank is provided with trunnions 22, the axes of which correspond to the axis 20 of the gear sector 21 and which are adapted to slide within the inclined slots or guide-ways 23 on opposite sides of the bell crank, the function of these guide-ways being to hold the sector in mesh with the rack. As 25 the end 17 of the bell crank is moved upwardly in applying the brakes the bell crank rocks upon the inclined rack 19 and moves downwardly and away from the brakes and at the same time winds the chain 15 upon 30 the surface 18. On the release of the brakes the reverse action takes place.

The power applying mechanism 12 consists of a housing 24 secured by means of lugs 25 to the body of the car. The inner 35 and outer walls of the housing are provided with vertical slots or guide-ways 26 in which the winding shaft 27 is adapted to operate. The shaft 27 is supported so as to be capable of moving vertically in the 40 guide-ways by flexible elements, such as chains 28, secured to the upper end of the housing in any suitable manner. The winding shaft 27 is provided with arms 29, to which the chains 28 are secured, these arms 45 serving to increase the initial take-up of the shaft on rotation thereof. The shaft is also provided with a central arm 30 to which is secured a flexible element, such as a chain 31, the other end of which is secured to the 50 tension rod 13. The diameter of the shaft 27 and the length of the arms 29 and 30 are so proportioned that the take-up of the apparatus on one rotation or less of the shaft 27 is sufficient to remove all slack from the 55 brake rigging, and to set the brakes. The length of the train section 31 need only be sufficient to wind once around the shaft 27, although it is obvious that it may be longer, if desired, and may take the place of rod 13. It is to be noted, however, that the shorter 60 the lengths of flexible chains and the like used in brake apparatus, the more certain the operation of the brake, inasmuch as the rigid elements, such as the tension rod 13 65 are not likely to be swayed out of place by

movement of the car and cannot become twisted or kinked.

The shaft 27 is provided with a projection 32, preferably polygonal in cross section to which is secured a ratchet wheel 33. 70 Pivoted on the shaft 27 is a hand lever 34 having a forked end 35 which engages the projection 32 on opposite sides of the ratchet 33. Pivoted to the hand lever 34 is a pawl 36, the rear end 37 of which is made sufficiently heavy to bring the forward end 38 into engagement with the ratchet, so that the shaft 27 may be rotated in a clockwise direction by an oscillation of the lever 34. The housing 24 may be provided with an open 80 sided housing 39 covered at the top and adapted to protect the ratchet and pawl and other moving parts from the action of snow and ice and cinders, and also to exclude such substances from entry into the housing 24 through the forward guide-way 26. When the hand lever 34 hangs freely downwardly the tail end 40 of the pawl 36 is adapted to engage the rear face 41 of the housing 39 so as to withdraw the pawl from engagement 85 with the ratchet for a purpose hereinafter described. If it is desired to dispense with the housing 39, a tripping surface which may be provided by the rear face 41 of the housing is employed to disengage the pawl 90 from the ratchet. The outer wall 42 in conjunction with the collar 43 on the shaft 95 serves to prevent any substantial endwise movement of the shaft 27.

The forward end of the shaft 27 is journaled in a block 44 adapted to slide vertically in the guide-way 26. A pawl 45 is pivoted to the block 44 and when in engagement with the ratchet 33 serves to prevent the rotation of the shaft 27 in counter-clockwise direction as shown in Fig. 3. A pivoted weight 46 having preferably the same pivot as the pawl 45, serves, when in the position shown in Fig. 3, to hold the pawl 45 in engagement with the ratchet 33. 100 When thrown over to the left so that the weight engages the lug 47 on the pawl 45, the weight is adapted to lift the pawl out of engagement with the ratchet 33, when pressure thereon is relieved. 110

A pin 48 projecting from the face of the housing 24 is adapted to engage a web 49 projecting from the weight 46, when the same is thrown over to the left, so as to return it to operative position, as shown in 120 Fig. 3, when the shaft 27 reaches its lower position on release of the brakes.

Operation: The shaft 27 is rotated by an oscillation of the hand lever 34 and winds the chain 31 thereon, at the same time winding itself upon the chain 28 and rising in the guide-ways 26. The initial rotation produces a relatively great movement of the tension rod 13 and serves to remove all slack 125 from the brake rigging and to bring the 130

brake shoes in contact with the wheels. Further rotation of the shaft winds the chains 28 and 31 around the relatively small shaft 27, resulting in a slow, but powerful 5 pull upon the tension rod 13. The engagement of the pawl 45 with the ratchet 33 prevents the release of the brakes.

The release of the brakes may be accomplished by a brakeman (standing preferably, upon the stub platform 50) with one hand, the other hand being employed in grasping a handle to prevent his being accidentally thrown from the car. The weight 10 46 is first thrown over to the left so as to tend to raise the pawl 45 out of engagement with the ratchet 33. Pressure is then relieved from the pawl 45 by a slight movement of the hand lever 35, permitting the weight 46 to withdraw the pawl 45. The 15 hand lever is then permitted to fall, the engagement of the tail end 40 with the surface 41 withdrawing the pawl 36 from engagement with the ratchet 33. This disconnects the hand lever from the ratchet and 20 permits the shaft to rotate in a reverse direction and unwind the chains, thus effecting a release of the brakes. When the shaft 27 reaches its lowermost position, as 25 shown in Figs. 3 and 4, the weight 46 strikes the pin 48 and is thrown over into operative position, as shown in Fig. 3. This 30 effects an automatic resetting of the apparatus so that the brakes may be applied without any manual resetting of the apparatus.

I claim:

1. In combination with a railway car and its brakes, apparatus for manipulating the brakes comprising a winding member of relatively small diameter having an arm extending therefrom, a flexible element connected with the brakes and with said arm so that, on rotation of the winding member, the flexible element is given a movement of considerable amplitude through the swinging movement of the arm and is then wound around the portion of the member which is of small diameter, means for rotating said winding member and giving to the same a translatory movement, and means sharing the translatory movement of the winding member for retaining the same in any desired position of rotation.

2. In combination with a railway car and its brakes, apparatus for manipulating the brakes comprising a housing secured to the car, a winding member having arms extending therefrom, flexible connections secured to said housing and to said arms for supporting said winding member and adapted to wind thereon, an operating lever connected with said winding member for rotating the same, a tension rod connected with the brakes and having a flexible section, an arm on said winding member pro-

jecting in the opposite direction from the first named arms and having said flexible section connected thereto, and means associated with said housing and winding member for preventing the reverse rotation of 70 the winding member.

3. In combination with a railway car and its brakes, apparatus for manipulating the brakes comprising a supporting means secured to the car and having vertical guide-ways therein, a winding shaft in said guide-ways and flexible means for supporting said shaft in said supporting means, a tension rod connected with the brakes and having a flexible section thereon connected with said shaft and adapted to wind thereon, means for rotating said shaft, a block slid- 75 able in a guide-way associated with said shaft, and means for coupling said shaft to said block to prevent the reverse rotation 80 thereof.

4. In combination with a railway car and its brakes, apparatus for manipulating the brakes comprising a supporting means secured to the car and having vertical guide-ways therein, a winding shaft in said guide-ways and flexible means for supporting said shaft in said supporting means, a tension rod connected with the brakes and having a flexible section thereon connected with said shaft and adapted to wind thereon, means 90 for rotating said shaft, a block slid-able in a guide-way associated with said shaft, means for coupling said shaft to said block to prevent the reverse rotation thereof and means 95 for rendering said coupling means ineffective so as to permit the release of the brakes.

5. In combination with a railway car and its brakes, apparatus for manipulating the brakes comprising a supporting means secured to the car and having vertical guide-ways therein, a winding shaft in said guide-ways and flexible means for supporting said shaft in said supporting means, a tension rod connected with the brakes and having a flexible section thereon connected with said shaft and adapted to wind thereon, means for rotating said shaft, a block slid-able in a guide-way associated with said shaft, a ratchet on said shaft and a pawl on said block 105 engaging said ratchet to prevent the reverse rotation of said shaft.

6. In combination with a railway car and its brakes, apparatus for manipulating the brakes comprising a supporting means secured to the car and having vertical guide-ways therein, a winding shaft in said guide-ways and flexible means for supporting said shaft in said supporting means, a tension rod connected with the brakes and having a flexible section thereon connected with said shaft and adapted to wind thereon, means for rotating said shaft, a block slid-able in a guide-way associated with said shaft, a ratchet on said shaft, a pawl on said block 110 115 120 125 130

engaging said ratchet to prevent the reverse rotation of said shaft and means for rendering said pawl ineffective so as to permit the release of the brakes.

- 5 7. In combination with a railway car and its brakes, apparatus for manipulating the brakes comprising a supporting means secured to the car and having vertical guide-ways therein, a winding shaft in said guide-ways and flexible means for supporting said shaft in said supporting means, a tension rod connected with the brakes and having a flexible section thereon connected with said shaft and adapted to wind thereon, means 10 for rotating said shaft, a block slidable in a guide-way associated with said shaft, a ratchet on said shaft, a pawl on said block engaging said ratchet to prevent the reverse rotation of said shaft, and a weight to hold 15 said pawl in engagement with said ratchet which may be set to hold said pawl out of engagement with said ratchet so as to permit release of the brakes.

8. In combination with a railway car and 25 its brakes, apparatus for manipulating the brakes comprising a supporting means secured to the car and having vertical guide-ways therein, a winding shaft in said guide-ways and flexible means for supporting said 30 shaft in said supporting means, a tension rod connected with the brakes and having a flexible section thereon connected with said shaft and adapted to wind thereon, means for rotating said shaft, a block slidable in 35 a guide-way associated with said shaft, a ratchet on said shaft and a pawl on said block engaging said ratchet to prevent the reverse rotation of said shaft, and a weight pivoted to said block and adapted in one 40 position to hold said pawl in engagement with the ratchet and in the other position to tend to lift the same out of engagement with said ratchet so as to permit the release of the brakes.

- 45 9. In combination with a railway car and its brakes, apparatus for manipulating the brakes comprising a housing secured to the car and having a vertical guide-way therein, a slidable block in said guide-way, a 50 winding shaft having a ratchet thereon journaled in said block and supported in said housing by flexible means adapted to wind on said shaft, a tension rod connected with said brakes and having a flexible section 55 connected with said shaft, means for rotating said shaft to set the brakes, a pawl on said block engaging said ratchet for preventing the reverse rotation of said shaft, and a weight pivoted on said block for en- 60 gaging said pawl in one position to hold the same in engagement with said ratchet and in another position to tend to force said pawl out of engagement with said ratchet so as to release the brakes.

- 65 10. In combination with a railway car and

its brakes, apparatus for manipulating the brakes comprising a housing secured to the car and having a vertical guide-way therein, a slidable block in said guide-way, a winding shaft having a ratchet thereon journaled in said block and supported in said housing by flexible means adapted to wind on said shaft, a tension rod connected with said brakes and having a flexible section, 70 connected with said shaft, a hand lever having a pawl adapted to engage said ratchet for rotating said shaft to set the brakes, a pawl on said block engaging said ratchet for preventing the reverse rotation of said shaft, and a weight pivoted on said block 75 for engaging said pawl in one position to hold the same in engagement with said ratchet and in another position to tend to force said pawl out of engagement with said ratchet so as to release the brakes.

11. In combination with a railway car and its brakes, apparatus for manipulating the brakes comprising a housing secured to the car and having a vertical guide-way therein, a slidable block in said guide-way, a winding shaft having a ratchet thereon journaled in said block and supported in said housing by flexible means adapted to wind on said shaft, a tension rod connected with said shaft, a hand lever having a pawl adapted to engage said ratchet for rotating said shaft to set the brakes, a pawl on said block engaging said ratchet for preventing the reverse rotation of said shaft, a weight pivoted on said block for engaging said pawl in one position to hold the same in engagement with said ratchet and in another position to tend to force said pawl out of engagement with said ratchet so as to release the brakes, and means for engaging said lever pawl to force the same out of engagement with said ratchet whereby the lever is disconnected from said shaft.

12. In combination with a railway car and its brakes, apparatus for manipulating the brakes comprising a housing secured to the car and having a vertical guide-way therein, a slidable block in said guide-way, a winding shaft having a ratchet thereon journaled in said block and supported in said housing by flexible means adapted to wind on said shaft, a tension rod connected with said brakes and having a flexible section connected with said shaft, a hand lever having a pawl adapted to engage said ratchet for rotating said shaft to set the brakes, a pawl on said block engaging said ratchet for preventing the reverse rotation of said shaft, a weight pivoted on said block for engaging said pawl in one position to hold the same in engagement with said ratchet and in another position to tend to force said pawl out of engagement with said ratchet so as to release the brakes, and means on said housing adapted to be en- 125

- gaged by said lever pawl when said lever and to said brakes, a pawl on said block for 65
is in one position to force said pawl out
of engagement with said ratchet whereby
the lever is disconnected from said shaft.
- 5 13. In combination with a railway car
and its brakes, apparatus for manipulating
the brakes comprising a housing secured
to the car and having a vertical guide-way
therein, a slidable block in said guide-way,
10 a winding shaft having a ratchet thereon
journaled in said block and supported in
said housing by flexible means adapted to
wind on said shaft, a tension rod connected
with said brakes and having a flexible sec-
15 tion connected with said shaft, a hand lever
having a pawl adapted to engage said ratchet
for rotating said shaft to set the brakes,
a pawl on said block engaging said ratchet
for preventing the reverse rotation of said
20 shaft, a weight pivoted on said block for
engaging said pawl in one position to hold
the same in engagement with said ratchet
and in another position to tend to force
said pawl out of engagement with said
25 ratchet so as to release the brakes, a tri-
pping surface extending from said housing
and adapted to be engaged by the opposite
end of said lever pawl when said lever is
in one position to force said pawl out of
30 engagement with said ratchet whereby the
lever is disconnected from said shaft.
14. In combination with a railway car
and its brakes, apparatus for manipulating
the brakes comprising a supporting means
35 secured to the car and having vertical
guide-ways therein, a winding shaft in said
guide-ways and flexible means for support-
ing said shaft in said supporting means, a
tension rod connected with the brakes and
40 having a flexible section thereon connected
with said shaft and adapted to wind there-
on, means for rotating said shaft, a block
slidable in a guide-way associated with
said shaft, a ratchet on said shaft,
45 a pawl on said block for engaging said
ratchet to prevent the reverse rotation
of said shaft, a weight to hold said pawl in
engagement with said ratchet which may be
set to hold said pawl out of engagement
50 with said ratchet so as to permit release of
the brakes, and a projection on said housing
adapted to engage said weight when the
brakes have been released to throw the same
into operative engagement with said pawl.
- 55 15. In combination with a railway car
and its brakes, apparatus for manipulating
the brakes comprising a housing secured to
the car and having vertical guide-ways
therein, a slidable block in one guide-way, a
60 winding shaft having a ratchet fixed thereto
journaled in said block and supported in
said housing by chains, a projection extend-
ing from the winding surface of said shaft,
a tension chain connected to said projection
- engaging said ratchet to prevent reverse ro-
tation of the shaft, a hand lever having a
pawl adapted to engage said ratchet for
rotating said shaft to set the brakes, a pawl
on said block engaging said ratchet for pre-
venting the reverse rotation of said shaft, a
weight pivoted on said block for engaging
said pawl in one position to hold the same
in engagement with said ratchet and in an-
other position to tend to force said pawl out
of engagement with said ratchet so as to re-
lease the brakes, and means for engaging
said lever pawl to force the same out of en-
gagement with said ratchet whereby the
lever is disconnected from said shaft. 80
16. In combination with a railway car
and its brakes, apparatus for manipulating
the brakes comprising a housing secured to
the car and having vertical guide-ways
therein, a slidable block in one guide-way,
85 a winding shaft having a ratchet fixed thereto
journaled in said block and supported in
said housing by chains, a chain connected to
said shaft and to said brakes, a pawl on said
block for engaging said ratchet to prevent
90 reverse rotation of the shaft, a hand lever
having a pawl adapted to engage said
ratchet for rotating said shaft to set the
brakes, a pawl on said block engaging said
ratchet for preventing the reverse rotation
95 of said shaft, a weight pivoted on said block
for engaging said pawl in one position to
hold the same in engagement with said
ratchet and in another position to tend to
force said pawl out of engagement with
100 said ratchet so as to release the brakes, and
means for engaging said lever pawl to force
the same out of engagement with said
ratchet whereby the lever is disconnected
from said shaft. 105
17. In combination with a railway car
and its brakes, apparatus for manipulating
the brakes comprising a housing secured to
the car and having vertical guide-ways
110 therein, a slidable block in one guide-way,
a winding shaft having a ratchet fixed thereto
journaled in said block, arms project-
ing from the winding surface of said
shaft, chains connected to said arms for
115 supporting said shaft in said housing and a
chain connected with an arm and with said
brakes, a hand lever having a pawl thereon
engaging said ratchet for rotating said
shaft whereby said chains are simultane-
ously wound on said shaft, a pawl on said block
120 for engaging said ratchet for preventing the
release of the brakes and a weight pivoted to
said block adapted to engage said pawl in
one position to cause the same to engage
said ratchet and in the other position to
tend to disengage said pawl from said
ratchet. 125
18. In combination with a railway car and

its brakes, apparatus for manipulating the brakes, comprising a housing, a winding member in said housing and capable of translatory movement therein, a flexible element connected with the brakes and the said member, a flexible member connected with the housing and with said member, means

for rotating said winding member and thus imparting a translatory movement thereto, and means sharing the translatory movement with the winding member for retaining the same in any desired position of rotation.

AUGUSTUS F. KLASING.
